UNITED STATES PATENT OFFICE.

WILLIAM N. MCINNIS, OF BELVIDERE, NEW JERSEY, ASSIGNOR OF TWO-THIRDS TO JOSEPH H. WILSON, HENRY S. HARRIS, CHARLES E. HARRIS, AND ROBERTA R. HARRIS, OF BELVIDERE, NEW JERSEY.

BRAKE FOR RAILWAY-CARS.

SPECIFICATION forming part of Letters Patent No. 698,310, dated April 22, 1902.

Application filed February 21, 1901. Serial No. 48,300. (No model.)

To all whom it may concern:

Be it known that I, WILLIAM N. MCINNIS, a citizen of the United States, and a resident of Belvidere, in the county of Warren and State 5 of New Jersey, have made a certain new and useful Invention in Brakes for Railway-Cars; and I declare the following to be a full, clear, and exact description of the same, such as will enable others skilled in the art to which it applies 10 to make and use the invention, reference being had to the accompanying drawings, and to letters of reference marked thereon, which form a part of this specification.

Figure 1 is a side elevation of my invention 15 as applied. Fig. 2 is a cross-section on the line 2 2, Fig. 1.

The invention has relation to track-brakes for railway-cars; and it consists in the novel construction and combination of parts, as hereinafter set forth.

In the accompanying drawings the letters A A represent the framework of trucks of a car, parts of which only are shown.

B B indicate strong metal plates or lugs of 25 said trucks, to which are pivoted the upper toggle-bars C, these being pivoted to the lower toggle-bars C' and to the transverse rod e, to which the piston-rod F is connected.

D represents the brake-shoe, which is pivoted 30 to a transverse shoe rod or bar b, which is about as long as the track is wide and carries a brake-shoe at each end. This bar b is connected to the lower end of the toggle-bar C' and to the lower end of a pivoted strut or brace-bar E, which is pivoted to the truck-frame at d.

The brace-bar E and the lower toggle-bar C' are oppositely inclined, diverging upwardly

from their connection to the transverse bar b. In this manner is formed a compound 40 three-arm toggle, having the brake-shoe bar in the lower angle and the piston-bar in the upper angle. This forms a combined lengthwise and vertical toggle device. In this construction the pivoted strut or brace may be 45 connected to the lower part of the truck.

When the brake is to be applied, the power-cylinder is operated in the usual manner to force the piston-rods toward the trucks, so that their action tends to straighten the vertical branches of the toggle—that is to say, to render its angle less acute—while at the same time the longitudinal toggle-bars are caused to approach each other at a more acute angle in such wise that great pressure is exerted on 55 the brake-shoes and through said shoes on the rails. Reverse movement of the piston-rods relieves the pressure and lifts the brake-shoes.

Having described this invention, what I 60 claim, and desire to secure by Letters Patent, is—

In a track-brake for railway-cars, the shoes, the brace bars or links having a pivotal connection with said shoes, and with the truck-frame, the toggle-levers having a pivotal connection with said shoes, and with the truck-frame, and means for operating said toggles, substantially as specified.

In testimony whereof I affix my signature 70 in presence of two witnesses.

WILLIAM N. MCINNIS.
